(57) **ABSTRACT**

A positioning structure for a clipboard contains a first cover and a second cover. Two grooves are formed on a connection of the first cover and the second cover. The first cover includes two first recesses, and the second cover includes two second recesses, two retainers are attached in the two first recess and the two second recess. The first cover also includes a first slot, a second slot, and a third slot. The second cover also includes a first notch, a second notch, and a third notch. Each of plural positioning members includes an integrally formed abutting block, an actuating section, a first inserting piece, two second inserting pieces, and a cutout. The plural positioning members are inserted in or removed from the first slot, the second slot, the third slot, the first notch, the second notch, the third notch by using a plurality of first inserting pieces.

FIG. 1

FIG. 2

FIG. 3

FIG. 4

FIG. 5

FIG. 6

FIG. 7

1
POSITIONING STRUCTURE FOR A
CLIPBOARD

BACKGROUND OF THE INVENTION

1. Field of the Invention

The present invention relates to a positioning structure for a clipboard that is capable of positioning at least one positioning member in first and/or second covers based on requirement.

2. Description of the Prior Art

A conventional clipboard includes first and second covers to be closed together, and at least one retainer to retain the first and second covers together. The first and the second covers are made in two different molds respectively, thus increasing production cost.

Moreover, a paper or a catalog is placed in the clipboard, but the paper or the catalog can not be fixed in the clipboard securely.

The present invention has arisen to mitigate and/or obviate the afore-described disadvantages.

SUMMARY OF THE INVENTION

The primary objective of the present invention is to provide a positioning structure for a clipboard that is capable of positioning at least one positioning member in first and/or second covers based on requirement.

Another objective of the present invention is to provide a positioning structure for a clipboard of which first and second covers are integrally formed by using a mold to lower production cost.

To obtain the above objectives, a positioning structure for a clipboard provided by the present invention contains:

a first cover and a second cover, both of which are integrally formed by a mold and correspond to each other, with two grooves formed on a connection of the first and second covers to retain two retaining members respectively so that the clipboard is opened and closed; the first cover including two first recesses disposed on one side thereof, and the second cover including two second recesses fixed on one side thereof individually, with two retainers attached in the first and second recesses so that the first and second covers are locked together by using the retainers individually; the first cover also including a first slot disposed on another side thereof, a second slot fixed on one end side thereof, and a third slot formed on another end side thereof; the second cover also including a first notch disposed on another side thereof, a second notch fixed on one end side thereof, and a third notch formed on another end side thereof;

wherein each positioning member includes an integrally formed abutting block, an actuating section fixed thereon, a first inserting piece extending downward from a rear side of the abutting block, two inserting pieces attached on two sides of the first inserting piece individually, and a cutout formed on the first inserting piece.

BRIEF DESCRIPTION OF THE DRAWINGS

FIG. 1 is a perspective view showing the assembly of a clipboard according to a preferred embodiment of the present invention;

FIG. 2 is a plan view showing the assembly of the clipboard according to the preferred embodiment of the present invention;

2

FIG. 3 is a perspective view showing the assembly of a positioning structure for the clipboard according to the preferred embodiment of the present invention;

FIG. 4 is an exploded perspective view showing the positioning structure for the clipboard according to the preferred embodiment of the present invention;

FIG. 5 is a perspective view showing the assembly of a positioning structure for the clipboard according to the preferred embodiment of the present invention;

FIG. 6 is an amplified cross sectional of a part A of FIG. 3 and taken along the line B-B' of FIG. 3; and

FIG. 7 is a perspective view showing the operation of the positioning structure for the clipboard according to the preferred embodiment of the present invention.

DETAILED DESCRIPTION OF THE PREFERRED EMBODIMENTS

The present invention will be clearer from the following description when viewed together with the accompanying drawings, which show, for purpose of illustration only, the preferred embodiments in accordance with the present invention.

Referring to FIGS. 1-4, a positioning structure for a clipboard in accordance with a preferred embodiment of the present invention comprises a first cover 11 and a second cover 12, both of which are made by a mold and correspond to each other. Two grooves 13, 14 are formed on a connection of the first and the second covers 11, 12 to retain two retaining members 21, 22 respectively so that the clipboard is opened and closed. The first cover 11 includes two first recesses 17, 18 disposed on a front outer side of the first cover 11, and the second cover 12 includes two second recesses 15, 16 fixed on a rear outer side of the second cover 12. Two retainers 23, 24 are attached in the first and second recesses 17, 18 so that the first and second covers 11, 12 are locked together by using the retainers 23, 24 individually. The first cover 11 also includes a first slot 31 disposed on a rear inner side of the first cover 11, a second slot 331 fixed on a right inner side of the first cover 11, and a third slot 33 formed on a left inner side of the first cover 11. The second cover 12 also includes a first notch 32 disposed on a front inner side of the second cover 12, a second notch 341 fixed on a left inner side of the second cover 12, and a third notch 34 formed on a right inner side of the second cover 12.

As shown in FIGS. 4-6, the first, second, and third slots 31, 331, 341 of the first cover 11 and the first, second, and third notches 32, 33, 34 of the second cover 12 are integrally formed in the first and second covers 11, 12 respectively to insert at least one positioning member 40. Each positioning member 40 includes an integrally formed abutting block 41, an actuating section 42 fixed thereon, a first inserting piece 44 extending downward from a rear side of the abutting block 41, two inserting pieces 43 attached on two sides of the first inserting piece 44 individually, and a cutout 45 formed on the first inserting piece 44. Thereby when the positioning member 40 is selectively inserted in the first, second, and third slots 31, 331, 341 of the first cover 11 and the first, second, and third notches 32, 33, 34 of the second cover 12, the first inserting piece 44 is placed in the first slot 31, and a horizontal rib 35 of the first slot 31 is retained in the cutout 45 of the first inserting piece 44 to position the positioning member 40 securely. A projection 46 fixed on a bottom end of the positioning members 40 is provided to abut against a document, and the actuating section 42 is used to make a user move the abutting block 41 upward to release an engagement of the document.

3

Furthermore, the positioning member **4.0** is capable of being engaged with or disengaged from the first, second, and third slots **31, 331, 341** of the first cover **11** and the first, second, and third notches **32, 33, 34** of the second cover **12** selectively.

In operation, as shown in FIG. 7, the positioning member **40** is inserted in the first slot **31** of the first cover **11**, and there is no positioning member **40** secured in the second cover **12** so that a first paper **50** positioned in the first cover **11** is pressed to be further fixed by ways of the positioning member **40**, and second paper **51** of the second cover **12** is placed randomly. Thereafter, as illustrated in FIG. 7, the first slot **31** of the first cover **11** includes the positioning member **40**, and the third notch **34** of the second cover **12** also includes another positioning member **40**, such that the positioning member **40** is capable of being fixed at any desired position based on requirement. Furthermore, two positioning members **40** are capable of being provided simultaneously so that different formats of documents are taken or read.

While various embodiments in accordance with the present invention have been shown and described, it is clear to those skilled in the art that further embodiments may be made without departing from the scope of the present invention.

What is claimed is:

1. A positioning structure for a clipboard comprising:
an integrally molded first cover comprising:
a front outer side having:
two recesses,
two locking members respectively disposed within
the two recesses;
a rear inner side having:
a first slot,
a second slot; and,

4

a left inner side having a third slot;
an integrally molded second cover cooperating with the
first cover, the second comprising:
a front inner side having a first notch;
a left inner side having a second notch; and,
a right inner side having a third notch;
a connection member retaining the second cover to the first
cover and comprising:
two grooves; and,
two retaining members respectively disposed in said two
grooves, the two retaining members enabling the clipboard
to be opened and closed;
a plurality of positioning members, each of the positioning
members comprising:
an integrally formed abutting block having a rear side;
an actuating section;
a first inserting piece having two sides and a cutout, the
first inserting piece extending downward from the
rear side of the abutting block; and,
two second inserting pieces respectively attached to the
two sides of the first inserting piece;
wherein a first positioning member of said plurality of
positioning members is inserted into the first slot, the
second slot, or the third slot; and,
wherein a second positioning member of said plurality of
positioning members is inserted into the first notch, the
second notch, or the third notch.

2. The positioning structure for the clipboard as claimed in
claim 1, wherein the first slot of the rear inner side of the first
cover further comprises a horizontal rib retained within the
cutout of the first inserting piece of the first positioning mem-
ber of said plurality of positioning members.
